RACK FOR BOOKS OR THE LIKE

Donald W. Crisp, Rte. 2, Maryville, Tenn.

Filed Oct. 19, 1962, Ser. No. 72,195

Term of patent 14 years

(Cl. D80—10)

FIG. 1

FIG. 2

FIG. 3

FIG. 4

FIGURE 1 is a front perspective view of a rack for books or the like embodying my new design;

FIGURE 2 is an enlarged front elevational view thereof;

FIGURE 3 is an enlarged side elevational view thereof; and

FIGURE 4 is an enlarged top plan view thereof.

I claim:

The ornamental design for a rack for books or the like, substantially as shown.
